Germany

Application August 10, 1950, Serial No. 178,576
In Germany August 20, 1949

3 Claims. (Cl. 292—281)

1

This invention relates to hasps and the like. In known hasps the main part, which is hinged to the fixed part and has at its free end a slot for the insertion of a staple, forms a continuous, rigid member in one piece which is straight throughout. In consequence, the hasp can be properly applied only to flat surfaces. If the main part of the hasp is made of wire, it is true that adaptation to curved surfaces is possible by subsequently bending the wire part to shape. Since the subsequent bending takes place by hand without the use of suitable tools, the correct curvature is, however, only seldom achieved, while undesirable deformation of the member, for example twisting, easily occurs. If the hasp is composed entirely of sheet metal, subsequent curving of the main part thereof is not possible owing to the stiffening thereof by rolling or turning over the longitudinal edges of the metal sheet forming the part.

The present invention aims at obviating the foregoing disadvantages and to this end and in contradistinction to the prior proposals, consists in a hasp wherein the hinged or main part of the hasp is adapted to be curved perpendicularly to its surface in the manner of a flexible chain, said part being constituted at least in part by a plurality of members hinged to one another. As can easily be seen, the effect is thereby achieved that the hasp can also be tightly applied to curved surfaces, and that it can automatically adapt itself to the greater or lesser curvature of the surface against which it bears. In addition, the advantage is also achieved that by having a large number of hinge pins considerable transverse stiffening is effected, so that the hasp affords greater resistance to attempted forcible breaking open.

If the hasp consists of sheet metal except for its hinge pins, the articulations connecting the members of the main part of the hasp, and preferably also the hinge serving to mount said part on the fixed part of the hasp, can have double hinges. This gives great flexibility so that the main part of the hasp can be curved over a relatively small radius without it being necessary to make the number of members, consisting of metal plates, excessively large.

The double hinges can each be formed from an oval ring of round steel, the strait parts of which (running perpendicularly to the longitudinal direction of the hasp) are adapted to turn in sockets formed at the ends of the metal plates. In a preferred embodiment of the invention, the double hinges can each consist of two pins

2

mounted in the sockets in the metal plates and connected at their ends outside the sockets by straps riveted thereto. By a simple method of manufacture great strength of the double joints, and hence great security against forcible breaking open of the hasp, can thereby be achieved. The pins and straps need merely be given suitable thickness. The straps, the thickness of which conveniently amounts to a multiple of the thickness of the metal plates of the hasp, consist preferably of hardened steel, so that they cannot be sawn through. Between the successive straps undetectably secured filling pieces can be mounted on the members of the hasp, which likewise consist of hardened steel and are of the same thickness as the straps. Since the straps and filling pieces fit tightly against each other, they form at each longitudinal edge of the articulated portion of the hasp a reinforcement rail of steel which, although it can be bent, is practically continuous, and which when it is attempted to break open the hasp by force prevents deformation of the latter and at the same time also protects this part of the hasp from being sawn or cut through.

In the drawing the invention is illustrated in one embodiment, and in said drawings:

Fig. 1 shows the front view of a hasp in the extended position;

Fig. 2 a rear view with a section through the line A—A of Fig. 3;

Fig. 3 is a longitudinal section through the line B—B of Fig. 2;

Fig. 4 is a cross section through the line C—C of Fig. 2; and

Figs. 5 and 6 are, respectively, a front view and section along the line D—D of Fig. 5, of a staple for use with the hasp.

The fixed part of the hasp illustrated consists of a sheet metal plate 2 provided with holes 4 for the passage of fixing screws, and a second and somewhat larger sheet metal plate 3 which is intended to cover said plate 2 and is articulated thereto by a hinge 4. The longitudinal edges of the covering plate 3 are bent over to the rear. The longitudinal edges, and also the transverse edge facing away from the hinge, of the fixed plate can conveniently also be bent over, but forwards.

The main part of the hasp is hinged to the covering plate 3 by means of a hinge 5. Said part, in the design according to the invention, is composed of a plurality of members 7, 8 connected together by hinges 6, so that it can be curved like a flexible chain. In the example, the members consist of two shorter metal plates 7 and a

longer metal plate 8 which forms the end member and which has a slot 9 to take a staple 33. The longitudinal edges 14 of the metal plates 1 and 8 are bent over to the rear in order to stiffen the plates. In order to permit considerable curvature of the hasp, both the hinges 6 and the hinge 5 are designed as double hinges, having each two pins firmly joined together at their ends and adapted to turn in sockets 11. The sockets 11, which extend perpendicularly to the longitudinal direction of the hasp and over the greater part of the width of the latter, are disposed on the rear side of the metal plates 3, 7, 8, at the adjoining ends of the latter, and are formed by cylindrically rolled extensions of the 15 plates.

The two pins of each double joint consist of two separate pins 26, which are connected together by two straps 27 riveted on at their stopped ends. The straps 27, the thickness of which amounts to a multiple of the thickness of the sheeting of the hasp members, are made of hardenable bar steel and hardened, while each strap may consist of two stampings which are pressed firmly on to one another when the rivet heads on the pins 26 are upset. The resulting double hinges are protected at the sides by the longitudinal edges 14, bent over to the rear, of the metal plates 7, 8 forming the members of the main part of the hasp and of the plate 3 of the fixed part.

Between the straps 27 of the successive double hinges, filling pieces 28 are disposed, which have substantially the same thickness as the straps. The filling pieces 28 are connected in pairs by sheet steel strips 29 lying between the hinge sockets 11 and spaced apart corresponding to the spacing of the straps of the double hinges. They are at the same time formed partly by the bent-over ends of the strips 29, but for the most part by hardened stampings of hardenable bar steel riveted thereto. Each filling piece 28 embraces the semi-cylindrical ends of the straps 27 with recesses provided on its faces in the shape of cylindrical segments, so that the filling pieces cannot fall out to the rear, while at the same time the straps 27 and the filling pieces 28 fit into one another substantially without a gap. In the lateral direction the filling pieces are supported by the bent-over edges 14 of the metal plate 7. At the same time they are also further secured against lateral displacement by the fact that hollow cams 30 impressed in the sheet metal strips 29 connecting them engage in recesses 31 which are impressed from the rear in the metal plates 7. They therefore cannot be removed even if it should be found possible to bend up the plate edges 14.

The thick straps 27 and the filling pieces 28 of equal thickness lie as tightly as possible against the bent-over longitudinal edges 14 of the sheet metal plates forming the hasps. As can be seen, they form two rails reinforcing the articulated portion of the hasp on its two longitudinal sides, which rails on the one hand prevent deformation of that part of the hasp and on the other hand, since they are made of hardened steel, make both sawing and cutting through virtually impossible.

The staple engaging in the slot 9 in the end portion 8 of the hasps consists of a U-shaped stirrup 33 of circular steel wire carried by a base-plate 32. Said staple is held on the plate 32 by a second sheet metal plate 34 riveted on to the former and placed with an oval hole 35 over the staple and engaging with parts 36 pressed in the shape of channels over the outwardly bent

ends 37 of the limbs of the wire stirrup 33. In order to prevent the U-stirrup from turning in the channel-shaped pressed portions 36, its ends 37 are slightly flattened on the underside. The metal plate 34, serving to secure the staple extends over the full extent of the baseplate 32 and, like the latter, is provided with holes for the passage of fastening screws, so that at the same time it acts as reinforcement for the baseplate.

Within the scope of the invention, various modifications of the embodiment illustrated, and also other embodiments and applications, are possible. Thus, the articulated main portion of the hasp could be made entirely or mainly of wire, a sheet metal end member 8 of the embodiment illustrated in the drawing being for example connected to the fixed part by a number of articulated chain members. These may each consist substantially of a U-shaped wire stirrup, the ends of the legs of which are rolled in the form of eyes around the middle part of the adjoining stirrup, while the sheet metal plate 8 having the slot for the passage of the staple is connected by a hinge socket to the middle part of the last wire stirrup.

We claim:

1. A flexible hasp comprising in combination, two elongated hasp end sections, one of said hasp end sections formed with a slot and adapted to engage in said slot a hasp clasp of a door; a base plate hingedly connected with the other of said hasp end sections for securing said other hasp end section and thereby said hasp to the door frame movably only in one plane normal to the door; at least one intermediate hasp section located between said hasp end sections in longitudinal direction of said hasp, the transversal edges of said hasp sections located adjacent to a transversal edge of another hasp section being inwardly rolled so that two adjacent edges constitute a pair of substantially cylindrical transversally extending sockets; and a plurality of connecting links, each of said connecting links including two transversely extending hinge pins and two elongated connecting plates fixedly securing the ends of said two hinge pins together, the hinge pins of each of said links passing through a pair of said transversal sockets so as to hingedly connect said hasp sections.

2. A flexible hasp comprising in combination, two elongated hasp end sections composed of a front wall and two longitudinally extending side wall portions, one of said hasp end sections formed with a slot and adapted to engage in said slot a hasp clasp of a door; a base plate hingedly connected with the other of said hasp end sections for securing said other hasp end section and thereby said hasp to the door frame movably only in one plane normal to the door; at least one intermediate hasp section composed of a front wall and two longitudinally extending side wall portions and located between said hasp end sections in longitudinal direction of said hasp, the transversal edges of said hasp sections located adjacent to a transversal edge of another hasp section being inwardly rolled so that two adjacent edges constitute a pair of substantially cylindrical transversally extending sockets; a plurality of connecting links, each of said connecting links including two transversally extending hinge pins and two elongated connecting plates fixedly securing the ends of said two hinge pins together, the hinge pins of each of said links passing through a pair of said transversal sockets so as to hingedly connect said hasp sections; and a plurality of flat filler plates,

each filler plate located between two connecting plates on one side of said hasp fixedly secured to the side wall portion of the hasp section located between the corresponding connecting links, said filler plates forming together with said connecting plates two flexible substantially continuous rails on either side of said hasp adjacent to and within said side wall portions of said hasp sections.

3. A flexible hasp comprising in combination, two elongated hasp end sections composed of a front wall and two longitudinally extending side wall portions, one of said hasp end sections formed with a slot and adapted to engage in said slot a hasp clasp of a door; a base plate hingedly connected with the other of said hasp sections for securing said other hasp end section and thereby said hasp to the door frame movably only in one plane normal to the door; at least one intermediate hasp section composed of a front wall and two longitudinally extending side wall portions and located between said hasp end sections in longitudinal direction of said hasp, the transversal edges of said hasp sections located adjacent to a transversal edge of another hasp section being inwardly rolled so that two adjacent edges constitute a pair of substantially cylindrical transversally extending sockets; a plurality of connecting links, each of said connecting links including two transversally extending hinge pins and two elongated connecting plates fixedly securing the ends of said two hinge pins together, said connecting plates having rounded end portions, the hinge pins of each

5 of said links passing through a pair of said transversal sockets so as to hingedly connect said hasp sections; a plurality of flat filler plates, each filler plate located between two connecting plates on one side of said hasp engaging with two oppositely arranged recesses said rounded end portions of said connecting plates, and being fixedly secured to the side wall portion of the hasp section located between the corresponding connecting links, said filler plates forming together with said connecting plates two flexible substantially continuous rails on either side of said hasp adjacent to and within said side wall portions of said hasp sections; and strips secured to and connecting each two filler plates secured to one hasp section, each strip having a projection and engaging therewith a recess in the adjacent face of said front wall of the associated hasp section.
